UNITED STATES PATENT OFFICE

165,386

FABRIC OR THE LIKE FOR GRILLS OF RADIOS

John A. MacIntyre, Barrington, R. I.

Application November 18, 1950, Serial No. 13,042

Term of patent 14 years

(Cl. D92—1)

To all whom it may concern:—

Be it known that I, John A. MacIntyre, a citizen of the United States of America, residing at Barrington, county of Bristol, State of Rhode Island, have invented a new, original, and ornamental Design for a Fabric or the Like for Grills of Radios, of which the following is a specification, reference being had to the accompanying drawing, forming a part thereof.

The figure is a plan view of a fabric or the like for grills of radios, showing my new design.

I claim:

The ornamental design for a fabric or the like for grills of radios, substantially as shown.

JOHN A. MACINTYRE.
